UNITED STATES PATENT OFFICE.

HENRY J. GILBERT, OF SAGINAW, MICHIGAN.

FOLDING TABLE.

Application filed October 15, 1924. Serial No. 743,657.

My invention relates more particularly to folding ironing tables of the type in which an ironing board is provided with collapsible legs which may be folded up parallel with the board and in small compass, so that the table may be conveniently stored or set aside out of the way when not in use. In my copending application filed October 15, 1925, Serial No. 743,658 I have described a novel folding ironing board of this character which is particularly rigid, stable and efficient and in certain respects is similar to that hereinafter described, and in such application I have claimed the features of construction common to both applications and believed to be patentably novel. My present invention relates more particularly to a different novel construction and arrangement of the front leg of the table and the means for locking the collapsible leg structure in extended position, the essential elements of my invention being more particularly pointed out in the appended claims.

In the accompanying drawings, Figure 1 is a bottom plan view of the table with the legs folded; Fig. 2 is a side view of the table, with the legs extended to working position; Figs. 3 and 4 are detail views on a larger scale than that of the first three figures showing in central longitudinal section and front view, respectively, the construction of a sliding locking collar which in the extended position of the legs brings up against a stationary member on the under side of the board; Fig. 5 is a detail showing the pivotal connection of certain bracing members; Figs. 6 and 7 are details of a pivoted engagement of the rear legs with frame members, showing the arrangement of stop lugs for limiting the pivotal movement, and Fig. 8 is a detail side view showing a modified construction of locking collar.

The same reference characters indicate the same parts in all the figures of the drawing. The ironing board 1 of my novel ironing table is in the present instance secured to the folding leg structure through a transverse front bracket member 2 and a rear

bracket member 3, which may both be conveniently formed of metal strips formed with projecting ears or lugs at the ends and centrally to provide bearings in which the folding members may be pivoted. The legs and bracing members which constitute the folding structure may be formed of metal tubing, flattened as shown to facilitate jointing of the parts together.

The front leg 4 of the table, consisting of a centrally arranged shaft, is slotted at its inner end to straddle the bend 5 of the front bracket member 2, this bend constituting a pivoting lug to which the front leg member is pivoted. Bracing rods 6-6, riveted to the leg 4 near its outer end and pivoted to the lugs 7-7 at the ends of said frame member are provided to complete a folding, triangular, braced front leg structure.

The rear bracket member is angular in shape being formed with similar opposite portions making at the center of the board a broadly obtuse angle on its forward side. The bracket member is formed with a pair of central bearing lugs or ears 10-10, and with outer bearing lugs 11-11, to which latter the rear legs 12-12 of the table are pivoted. Bracing members 13-13 are provided which at their outer ends are secured respectively to the legs 12-12 at points intermediate their ends by a pair of inner rivets 14-14 respectively engaging the legs 12-12, the bracing members 13-13 and interposed spacing blocks 15-15; and by a pair of outer rivets or rivet pins 16-16, these rivet pins affording pivotal connections for other members of the folding leg structure. At their inner ends the bracing members 13-13 are pivoted to the bearing lugs 10-10 of the bearing strips, respectively.

The rear legs are connected to the front leg by means of a pair of connecting rods 19-19 pivoted respectively to the rivet pins 16-16 on the rear legs and also pivoted to the front leg on opposite sides thereof by means of a cross pin 18 extending through such leg and the bracing rods 6-6 near their

outer ends, which latter are flattened and offset to permit the flattened ends of the rods 19 to seat and nest in the bends so formed when the device is folded.

5 The folding leg structure thus far described is maintained in extended position when the device is unfolded for use by means of a pair of locking truss rods 17-17 pivoted respectively to the rear legs through 10 the rivet pins 16-16 and a common connected slide in the form of a locking collar or sleeve 20 pivoted between the front ends of such locking rods. This locking collar is arranged to slide on the front leg of the 15 table, and in the preferred form of my invention it is slit on its forward side and notched at the upper end of the slit to accommodate the bend 5 of the front bracket member, the outer ends of the notch being 20 slightly rounded, and the fit of the parts being snug, so that the spring action of the edges of the sleeve on opposite sides of its slit will tend to yieldingly hold the parts in engagement when forced together. This 25 spring action is supplemented to some extent by the forward thrust of the locking rods 17 tending to close the slit in the collar, and the notched engagement between the bend 5 of the bracket member and the notch 30 in the collar 20 prevents any rotative yielding of the collar, which materially aids in producing a rigid construction.

The top of the front leg and the inner or upper edge of the collar are cut at such an 35 angle that when the legs are in extended position the parts first mentioned will both bring up squarely against the face of the bracket member 2.

40 The rear legs 12, it will be noted (see Figs. 6 and 7) are formed with lugs 21 at the rear side of the inner or upper ends arranged to bring up against the edges of the rear bracket members when the legs are in fully extended position, to assist in giving 45 rigidity and stability to the leg structure in such position.

As is evident from a consideration of the 45 symmetrical oblique pivotal mounting of the rear legs, the feet of the two legs travel 50 in planes which are equally and oppositely inclined to the vertical plane of symmetry of the parts passing longitudinally through the center line of the board. The legs, moreover, are inclined outwardly from the 55 outer end of their pivotal bearings,—that is, each leg makes an obtuse angle with the line connecting its outer and inner points of support,—the proportions and arrangement of the parts with relation to the board 60 being such that the legs lie approximately parallel with and lie within the opposite margins of the board when the legs are in folded position, and spread outwardly and 65 way from each other beyond the vertical planes of such margins as the legs are un-

folded to extended position, thus giving a very broad footing and great stability to the table.

In Fig. 8 I have shown a modified form of means for locking the truss rods 17-17 in 70 extended position. In this modification the collar is not slotted and has no spring action, and its lower face is adapted to cooperate with a spring-pressed cam latch 25 pivotally mounted inside the front leg 4 and 75 projecting through a slot therein.

I claim:

1. In a folding ironing table or the like, a board, a centrally arranged front leg pivotally connected to the board, a pair of rear legs pivotally connected to the board, connecting rod means pivoted to said front leg and also pivotally connected with said rear legs, and a locking rod member pivotally connected with said rear legs intermediate 85 their ends and slidably connected with said front leg.

2. In a folding table or the like, a board, a front leg pivotally connected to the board, a pair of rear legs pivoted to opposed bearing members arranged in divergent relation and arranged to spread apart when moved from closed to extended position, a pair of connecting rods pivoted to said front leg near its foot and also severally pivotally 95 connected with said rear legs at points intermediate their ends, and a pair of locking rods severally pivotally connected with said rear legs at intermediate points and equipped with a common locking member 100 slidably mounted on said front leg.

3. In a folding ironing table or the like, a board, a pair of rear legs pivotally connected to the board, a bracket member equipped with a central pivoting lug, a front leg member notched at its inner end to engage said lug and pivoted thereto, and a folding locking rod member pivotally connected with said rear legs intermediate 110 their ends and equipped with a sliding collar engaging said front leg member, said collar being arranged to clampingly engage said pivoting lug when the locking rod member is in extended position.

4. A folding table comprising a table top and front and rear pivoting lugs secured thereto, a centrally arranged front leg structure pivoted to said front lugs and including a central member and diagonally arranged bracing members, a pair of rear legs pivoted to said rear pivoting lugs, said rear legs being set on oppositely inclined axes, whereby said legs are arranged to spread outwardly when unfolded, a pair of connecting rods pivoted to said front leg structure near its foot and also respectively pivoted to said rear legs at points intermediate their ends, and a pair of locking rods pivoted at one end to said rear legs at points intermediate 125 their ends, the opposite ends of said lock-

ing rods being connected with a common locking member slidably mounted on said central member of the front leg.

5. In a folding ironing table or the like, a front leg consisting of a centrally arranged shaft hinged to the table top and having a slide thereon, a pair of rear legs pivotally connected to said table top, a pair of connecting rods pivoted to said front leg

near its foot and also pivotally connected 10 with said rear legs at intermediate points thereon, and a pair of locking truss rods severally pivotally connected with said rear legs at intermediate points thereon, said locking truss rods being connected with said 15 slide.

HENRY J. GILBERT.
